UNITED STATES PATENT OFFICE

WILFRED G. JOHNSON, OF ELYRIA, OHIO, ASSIGNOR TO THE COLSON COMPANY, OF ELYRIA, OHIO, A CORPORATION OF OHIO

CASTER

Application file April 8, 1927. Serial No. 181,992.

My invention relates to casters and more particularly it relates to an improved expanding mechanism for retaining a caster pintle within a pintle receiving socket.

5 An object of my invention is to provide an improved expanding retaining mechanism for casters capable of adjustment whereby it may have frictional engagement with the side walls of sockets of varying dimensions.

10 Another object of my invention is to provide an improved caster retaining mechanism adaptable to securely engage the side walls of a socket and retain the caster from accidental disengagement therefrom and which 15 comprises a minimum number of parts and which is rigid in construction whereby it is capable of withstanding the usual rough usage.

Another object of my invention resides in 20 the provision of an improved caster retaining mechanism which may be expeditiously inserted into and rigidly retained within a caster socket.

These and other objects of my invention 25 and the invention itself will become apparent from reference to the following description of an embodiment of my invention and in which embodiment reference will be had to the accompanying drawings forming a part 30 of the specification.

Referring to the drawings:

Fig. 1 is a side elevational view of an embodiment of my invention illustrating the caster socket in longitudinal medial section; 35 Fig. 2 is a vertical, medial sectional view of the foregoing embodiment, some of the parts being illustrated in elevation;

Figs. 3, 4 and 5 are side elevational, vertical medial, sectional, and top plan views, respectively, of an expansible element employed in the foregoing embodiment, Fig. 4 being taken on the line 4-4 of Fig. 3; and

Fig. 6 is a fragmentary plan view of a blank prior to forming the same into the expansible element.

Referring to all of the figures of the drawings in all of which like parts are designated by like reference characters, my invention preferably comprises a caster 1 of the type 50 disclosed in one of the embodiments of my

prior application for Letters Patent entitled Casters, Serial No. 115,279, filed June 11, 1926, comprising a caster yoke member 3, a truncated cone member 30 having a depending bolt portion 31 extending downwardly 55 through a centrally disposed aperture 32 in the yoke and secured thereon by virtue of a nut 34. Said truncated cone is provided with a recessed upper surface 35 the purpose of which will hereinafter be described.

A plurality of anti-friction balls 36 are provided and are held interposed between the caster yoke top face and the truncated plate by means of an annularly flanged top plate 12, the flange of which being adapted to substantially enclose the bearing balls and have two-point engagement with the same. A centrally disposed aperture is formed in the top plate 12 for the reception of a reduced end of a caster stem or pintle 5, the pintle or stem being upset at 37 to rigidly secure the top plate and the pintle against relative movement. The upset head projects downwardly into the recessed wall 35 of the truncated cone 30 whereby relative movement between the upset head and the cone may be accomplished without frictional contact or rubbing between each other. An enlarged hexagonal portion 9 is formed in the stem adjacent the upset head 37 and abuts against the upper 60 face of the top plate 12 and spaces the upper face of the top plate from a frusto-conical expander sleeve 8 and provides a clearance 65 whereby a wrench may be inserted between the caster and sleeve to engage the portion 9 70 to turn the same. Said sleeve is centrally bored through which the stem projects and engages the hexagonal portion 9 and rests upon the same and supports the caster out of contact with the caster support. The 75 sleeve 8 is formed with an annular flange 26 which provides a support upon which a hollow tubular leg 24 of an article of furniture having a cylindrical caster socket 23 therein, may rest, said flange peripheral surface is 80 knurled to provide a suitable anti-slip gripping portion. The sleeve 8 is also formed with inclined side walls 20 which may project into the socket 23 of the leg 24, which 85 side walls terminate in a flattened top wall 39. 90

Threaded into the upper end of the caster stem is a second frustro-conical expander sleeve 19 having inwardly downwardly inclined side walls 21 terminating in a bottom flattened wall 51. Disposed about the pindle 5 and interposed between the sleeves 8 and 19 is a resilient sheet metal expansible frame 14 having a central disk portion 15 apertured centrally at 16 through which the 5
caster stem or pindle 5 projects, the disk portion 10
15 is preferably provided with integrally formed resilient arms 14 bent upwardly and downwardly therefrom alternately as shown at 18 to form the sides of the disk into a substantial hexagon in top plan view with the 15
resilient arms 14 disposed substantially parallel each with the other to form a resilient expansible skeleton frame which may be expanded or contracted by relative longitudinal 20
movement of the sleeves towards each other. The free ends of the resilient arms 14 are bent outwardly at 18 to form impinging portions 17 which are adapted to engage the inner side walls of the socket. The arms engage the inclined walls of the opposed sleeves 25
8 and 19 at the portions 18.

The expansible frame is preferably formed from a blank as illustrated in Fig. 6 of the drawings and the arm indicated at 40 may be 30
bent upwardly, the arm 41 may be bent downwardly and the arm 42 may then be bent upwardly and alternately and each are in sequence until all of the arms, preferably 6 in 35
number, have been bent upwardly or downwardly. The ends of the arms are then bent at right angles to the arms 14 to provide the impinging fingers 17.

A spring 22 may be disposed about the lower portion of the pindle 5 and compressed 40
between the central disk portion 15 of the frame and the upper wall 39 of the lowermost sleeve 8 and normally tend to urge the upwardly extending arms of the frame wedged between the inclined walls 21 of the sleeve 19 45
and the interior wall of the socket 23 to frictionally engage the fingers 17 with the socket thereby preventing accidental rotation of the sleeve 19 on the stem 5. It is to be understood, however, that such a spring is not essential 50
and may be dispensed with, if desired, I merely employ such a spring at times wherein the caster is applied to a supporting article and which may be subjected to undue vibrations which are apt to cause the sleeve 19 to accidentally rotate. 55

In applying a caster provided with my improved pindle retaining mechanism thereon, to a pindle receiving socket, the stem 5, sleeves 8 and 19 and frame 13 are inserted into the 60
socket and the hexagonal portion 9 is rotated by a suitable wrench which in turn rotates the pindle 5 causing the upper sleeve 19 to move downwardly on the threads 6 towards the sleeve 8. A wedge action takes place between the inclined walls 20 and 21, respective- 65

ly, of the sleeves 8 and 19 against the elbows or curved portions 18 of the arms 14 exerting a camming action thereon forcing the same outwardly and causing the fingers or impinging elements 17 to frictionally and securely engage the inner wall of the socket. The frictional engagement between the plurality of impinging fingers and the walls of the socket is sufficient to hold the caster securely in the socket. 70

In order to prevent rotation of the parts when a wrench is first applied to turn the hexagonal portion 9, an operator may grasp the flange 26 which is provided with the knurled surface by one hand while turning the hexagonal portion 9 with the free hand. The peripheral flange 26 of the sleeve providing a supporting wall 24 for the leg of the furniture relieves the expanding frame of any excess weight which might otherwise be exerted upon the same and tilting of the stem in the socket is eliminated. 80

Having thus described my invention in a specific embodiment, I am aware that numerous and extensive departures may be made from the embodiment herein illustrated and described but without departing from the spirit of my invention. 85

I claim:

1. In a caster retainer, the combination 90
with a caster support having a socket, a caster, a pindle supported thereby telescopable into the socket, a pair of superposed laterally tapered sleeves on the pindle, the upper sleeve being screw threaded onto the pindle, with its outer tapered surface disposed so as to converge downwardly, said other sleeve disposed at the lower end of the pindle and having its outer tapered surface converging upwardly, 95
said last named sleeve comprising a lateral flange disposed exteriorly of the support socket, said support resting upon said flange, an integral resilient sheet metal expansible frame disposed about the pindle and interposed between the sleeves, said frame provided with a transversely extending intermediate portion, a plurality of resilient arms projecting upwardly from the border of said frame transverse portion, and a plurality of similar arms projecting downwardly therefrom, the converging surfaces of said sleeves engageable with said arms to force the arms outwardly against the inner walls of the support socket when the stem is rotated relative to the upper sleeve. 100

2. Coupling means for leg supporting swivelable casters comprising a caster stem projected upwardly into a leg socket from the swiveling mechanism of the caster, a perforated plate supporting the leg, said stem rotatably projected through the perforation, said plate supported on the stem, a gripping element comprising a hub surrounding the stem, and a plurality of resilient arms integrally secured to the hub and extending longi- 105

tudinally and on different sides of the stem, and an expander for said arms adapted to be projected between their free ends, comprising a free nut, screw threaded on the stem, and a spring disposed within the socket exerting constant pressure against the hub to press the gripping element longitudinally of the stem to maintain continuous frictional engagement between the arms and the expander.

5 3. Coupling means for leg supporting swivelable casters comprising a caster stem projected upwardly into a leg socket from the swiveling mechanism of the caster, a perforated plate supporting the leg, said stem rotatably projected through the perforation, said plate supported on the stem, a gripping element comprising a hub surrounding the stem, and a plurality of resilient arms integrally secured to the hub and extending longitudinally and on different sides of the stem, and an expander for said arms adapted to be projected between their free ends, comprising a free nut, screw threaded on the stem, said gripping element being in the form of an

10 integral spider, having a central plate portion constituting said hub, said arms bent substantially rectilinearly from the border portion of the hub, other resilient arms integrally secured in like manner to alternately disposed border portions of said hub, extending longitudinally of the stem in the opposite direction to said first named arms, and expanding means supported by said plate within the socket for expanding the free ends of

15 said last named arms against the walls of the socket.
